US00D879636S

(12) United States Design Patent **(10) Patent No.:** **US D879,636 S**
Fan **(45) Date of Patent:** **** Mar. 31, 2020**

(54) LOCATOR

(71) Applicant: **UBISIGHT TECHNOLOGY LLC**,
Emerson, NJ (US)

(72) Inventor: **Chenglong Fan**, Beijing (CN)

(73) Assignee: **UBISIGHT TECHNOLOGY LLC**,
Emerson, NJ (US)

(**) Term: **15 Years**

(21) Appl. No.: **29/707,105**

(22) Filed: **Sep. 26, 2019**

(51) LOC (12) Cl. **10-05**

(52) U.S. Cl.

USPC **D10/104.2**

(58) **Field of Classification Search**

USPC D10/104.2, 65, 68, 70

See application file for complete search history.

(57) CLAIM

The ornamental design for a locator, as shown and described.

DESCRIPTION

FIG. 1 is a perspective view of a first embodiment of a locator showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1; and,

FIG. 10 is an enlarged view of portion 10 shown in FIG. 2. The broken lines in the drawings depict portions of the locator that form no part of the claimed design.
